JEWELRY FINDING OR SIMILAR ARTICLE

Murray Eibshutz, New York, N. Y., assignor to
Empco Metal Products Company, New York,
N. Y.

Application March 15, 1954, Serial No. 29,516

Term of patent 7 years

(Cl. D45—1)

To all whom it may concern:

Be it known that I, Murray Eibshutz, have invented a new, original, and ornamental Design for a Jewelry Finding or Similar Article, of which the following is a specification, reference being had to the accompanying drawing, forming a part hereof.

The figure in the drawing is a front view of the jewelry finding or similar article, showing my new design.

The article is of no substantial thickness.

I claim:

The ornamental design for a jewelry finding or similar article, substantially as shown and described.
